UNITED STATES PATENT OFFICE.

JOHN R. CAUTLEY, OF SOUTH BEND, INDIANA, ASSIGNOR TO BENDIX BRAKE COMPANY, OF CHICAGO, ILLINOIS, A CORPORATION OF ILLINOIS.

BRAKE SHOE.

Application filed October 12, 1925. Serial No. 62,078.

This invention relates to brake shoes, and is illustrated as embodied in novel shoes for a three-shoe-brake of a well-known type. An object of the invention is to provide an inexpensive but strong and rigid shoe, by building it up of parts capable of being stamped and cut from sheet metal.

5

In one desirable arrangement, a cylindrical lining-carrying part, preferably pressed to 10 the form of a shallow channel in cross-section to provide low edge-stiffening flanges, has secured centrally of its back a separate part forming a central stiffening web. In the illustrated embodiments, oppositely-extending 15 flanges secured to the lining-carrying part are formed on the central stiffening web, as for example by turning in opposite directions tongues cut in its edge, thus forming staggered series of attaching flanges.

20 According to another feature of the invention, the lining-carrying part is bent radially at one end, to form a cam-engaging portion centrally reinforced by the separate web.

These and other objects and features of the 25 invention, including various desirable novel details of construction, will be apparent from the following description of two illustrative embodiments shown in the accompanying drawing, in which:

30 Fig. 1 is a side elevation of the three shoes of the brake, in their assembled relation;

Fig. 2 is a section on the line 2—2 of Fig. 1, showing the construction of one of 35 the end shoes;

Fig. 3 is an inside elevation, in the direction of the arrows 3—3 in Fig. 1, of part of one of the end shoes;

Fig. 4 is a section corresponding to Fig. 2, but showing a modified construction of 40 shoe; and

Fig. 5 is a section through the central shoe, on the line 5—5 of Fig. 1.

The brake shown in Fig. 1 includes a central shoe 10 anchored at 12, a servo end shoe 14 pivoted to the central shoe at 16, and a reverse end shoe 18 anchored at 20. Shoes 14 and 18 are T-shaped in cross-section, while shoe 10 is channel-shaped, the 45 ends of shoes 14 and 18 extending into the ends of the channel to overlap or "cross-anchor" the shoes. Anchor 12 extends through a relatively large opening in shoe

18, so that it does not interfere with its movement, while anchor 20 either extends 55 through similar large openings in the sides of shoe 10, as fully described in French Patent No. 600,167, published February 1, 1926, or preferably is in the form of a pivot connecting shoe 18 to shoe 10.

60 The shoes are expanded against the usual brake drum by a suitable double cam arranged between the ends of shoes 14 and 18, against the resistance of return springs, one of which is connected between the free 65 ends of shoes 14 and 18 and the other of which is connected at one end to the end of shoe 10 and at its other end to the backing plate of the brake. This arrangement is more fully described in French Patent 70 No. 600,167.

75 Except as further described below, the above-listed parts or their equivalents may be of any desired construction. The present invention relates to the manner of constructing the brake shoes, some features being more especially applicable to shoes 14 and 18, which are preferably identical and interchangeable.

80 In the form shown in Figs. 2 and 3, each of these shoes includes a cylindrical lining-carrying part 22, the lining appearing at 24 in Fig. 1 but being omitted in the other figures. I prefer to press part 22 from sheet metal as a shallow channel in cross-section to provide low edge-stiffening flanges 26, and to bend it radially at its 85 end to provide a cam-engaging portion 28, Fig. 1, which may also have the low edge-stiffening flanges if desired.

90 The stiffening of the shoe is provided by a centrally-arranged part 30 (Figs. 2 and 3) or 130 (Fig. 4) secured to part 22 and serving to reinforce portion 28 along its center line. Part 30 has tongues 32 cut 95 along its edge and alternately bent in opposite directions to form two series of flanges secured to part 22 by spot-welding or riveting and extending away from each other toward the side edges of part 22. As 100 appears in Fig. 1, these two series of flanges also extend along portion 28, reinforcing it.

105 Part 130 (Fig. 4) is channel-shaped in cross-section, and has edge flanges 132 extending away from each other toward the

side edges of part 22, and welded or riveted to part 22.

As shown in Fig. 5, I prefer to make the central shoe 10 generally channel-shaped, with two stiffening webs 230, corresponding to the central web 30, but arranged near the opposite edges of the shoe and secured by the alternately-bent tongues 32.

Part 30 of shoe 18 extends far enough beyond the end of part 22 to extend into the channel of shoe 10, to provide for cross-anchoring the shoes if desired.

While two illustrative embodiments have been described in detail, it is not my intention to limit the scope of the invention to those particular embodiments, or otherwise than by the terms of the appended claims.

I claim:

1. A brake shoe having, in combination, a cylindrical part having approximately parallel side edges, and a separate stiffening part secured to the cylindrical part between said side edges to form a single-thickness stiffening web and projecting beyond and within the curve of the cylindrical part to form an integral pivot arm.

2. A brake shoe having, in combination, a cylindrical part having approximately parallel side edges, and a separate single-thickness stiffening part arranged between said side edges of the cylindrical part to form a stiffening web, and having flanges extending in opposite directions toward the edges of the cylindrical part and secured thereto.

3. A brake shoe having, in combination, a cylindrical part having approximately parallel side edges, and a separate stiffening part arranged between said side edges of the cylindrical part to form a stiffening web, and having a series of tongues secured to the cylindrical part.

4. A brake shoe having, in combination, a cylindrical part, and a one-piece part forming a stiffening web and having integral oppositely-bent flanges at its edge secured to said cylindrical part.

5. A brake shoe having, in combination, a cylindrical part, and a one-piece separate part forming a stiffening web and having integral oppositely-bent flanges at its edge secured to said cylindrical part, the flanges extending away from each other toward the side edges of the cylindrical part.

6. A brake shoe having, in combination, a cylindrical part, and a separate part forming a stiffening web and having tongues at its edge bent alternately in opposite directions to form oppositely-extending series of flanges staggered with respect to each other and secured to the cylindrical part.

7. A brake shoe having, in combination, a cylindrical part, and a separate part forming a stiffening web and having tongues at its edge bent alternately in opposite directions to form oppositely-extending series of

flanges staggered with respect to each other and secured to the cylindrical part, said part extending beyond the cylindrical part at one end and formed at that end to be mounted on a pivot.

8. A brake shoe having, in combination, a cylindrical part, and a separate part forming a stiffening web and having tongues at its edge bent alternately in opposite directions to form oppositely-extending series of flanges staggered with respect to each other and secured to the cylindrical part, said part extending beyond the cylindrical part at one end and formed at that end to be mounted on a pivot, and having an opening at an intermediate point for the pivot of a cross-anchored shoe.

9. A brake shoe having, in combination, a cylindrical part bent radially at one end to form a cam-engaging surface, and a separate part secured to the cylindrical part to form a stiffening web and reinforcing the radially-bent portion between its edges.

10. A brake shoe having, in combination, a cylindrical part in the form of a shallow channel in cross section to provide low stiffening flanges along its edges and bent radially at one end to form a cam-engaging surface having similar edge-stiffening flanges, and a separate part secured to the cylindrical part to form a stiffening web and reinforcing the radially-bent portion between its edges.

11. A brake shoe having a part bent radially at one end to provide a cam-engaging surface, and a stiffening web having oppositely-bent flanges engaging the back of the radially-bent portion to reinforce it.

12. A brake shoe having a part bent radially at one end to provide a cam-engaging surface, and a stiffening web having tongues bent alternately in opposite directions to form oppositely-extending series of flanges engaging the back of the radially-bent portion to reinforce it.

13. A brake shoe comprising a cylindrical outer part, and a stiffening member slotted radially from its outer edge forming tongues secured to the outer part, and having an unslotted portion projecting as a pivot arm beyond the end of the outer part.

14. A brake shoe comprising a cylindrical outer part, and a stiffening member slotted radially from its outer edge forming tongues bent alternately in opposite directions and secured to the outer part, and having an unslotted portion projecting as a pivot arm beyond the end of the outer part.

15. A brake comprising, in combination, a pair of shoes, each having a cylindrical outer part, one having an arcuate separate single stiffening member secured along its outer edge to its inner face, and the other having two parallel spaced stiffening members secured along their outer edges to its

inner face and projecting on opposite sides of one end of said single stiffening member to straddle said end.

16. A brake comprising, in combination, a pair of shoes, each having a cylindrical outer part, one having an arcuate stiffening web on its inner face, and the other having two parallel spaced stiffening members secured along their outer edges to its inner face and projecting on opposite sides of one end of said stiffening web to straddle said end.

17. A brake comprising, in combination, a pair of shoes, each having a cylindrical outer part, one having an arcuate separate single stiffening member secured along its outer edge to its inner face, and the other having two parallel spaced stiffening members secured along their outer edges to its inner face and projecting on opposite sides of one end of said single stiffening member to straddle said end, at least one of said stiffening members having oppositely-bent tongues secured to the inner face of its outer part.

18. A brake comprising, in combination, a shoe having a cylindrical outer part and a separate stiffening member secured along its outer edge to the inner face of said outer part and projecting beyond the end of the outer part, and another shoe having stiffening means including spaced projecting arms straddling the end of the projecting portion of the stiffening member.

19. A brake comprising, in combination, a shoe having a cylindrical outer part and a separate stiffening member having staggered sets of tongues along its outer edge secured to opposite sides of the inner face of said outer part and which member has a portion projecting beyond the end of the outer part, and another shoe having stiffening means including spaced projecting arms straddling the end of the projecting portion of the stiffening member.

20. A brake comprising, in combination, a central shoe including an outer cylindrical part and two parallel separate stiffening members secured along their outer edges to the inner face of said part, and a pair of end shoes having at their ends pivot arms projecting between the parallel stiffening members at opposite ends of the central shoe.

21. A brake shoe of pressed metal having a cylindrically-curved outer part (22) with its opposite sides stiffened by parallel integral flanges (26) projecting inwardly, and having a separate stiffening member (30) permanently secured to the inner face of the outer part (22) and extending substantially parallel to the integral flanges (26), the separate member (30) being substantially deeper than the integral flanges (26).

In testimony whereof, I have hereunto signed my name.

JOHN R. CAUTLEY.
